US00D856345S

(12) **United States Design Patent** (10) Patent No.: **US D856,345 S**
Clifford et al. (45) Date of Patent: **** Aug. 13, 2019**

(54) **DISPLAY SCREEN WITH GRAPHICAL USER INTERFACE FOR A MULTIMODE SURGICAL CONSOLE**

(71) Applicant: **Stryker Corporation**, Kalamazoo, MI (US)

(72) Inventors: **Steven Thomas Clifford**, Byron Center, MI (US); **Anna-Karin Soederstroem**, Morgan Hill, CA (US); **Sarah Garcia**, San Jose, CA (US)

(73) Assignee: **STRYKER CORPORATION**, Kalamazoo, MI (US)

(**) Term: **15 Years**

(21) Appl. No.: **29/602,200**

(22) Filed: **Apr. 28, 2017**

(51) LOC (12) Cl. **14-04**

(52) U.S. Cl.

USPC **D14/485**

(58) **Field of Classification Search**

USPC D14/485-495

(57) **CLAIM**

The ornamental design for a display screen with graphical user interface for a multimode surgical console, as shown and described.

DESCRIPTION

The FIGURE is a front view of a multimode surgical console having a display screen showing our new design.

The broken lines showing an electronic device illustrate environmental subject matter, whereas the broken lines showing a display screen and elements of the graphical user interface illustrate portions of the article. No subject matter depicted in broken lines form part of the claimed design.

1 Claim, 1 Drawing Sheet
